UNITED STATES PATENT OFFICE.

MAXIMILIAN STERN, OF NEW YORK, N. Y.

DIATHERMIC ELECTRODE.

Application filed January 12, 1926. Serial No. 80,720.

My present invention relates generally to electro-surgical instruments, and has particular reference to an electrode for the application of diathermy to an interior organ.

In the application of diathermy to organs of the body which are relatively inaccessible, such as organs in the nature of the prostate gland, instruments of the character heretofore utilized have presented grave technical difficulties and have entailed numerous disadvantages which have rendered the proper diathermic application extremely difficult and impractical, if at all possible.

It is among the more important objects of the present invention to provide an instrument which may be utilized for purposes of this character, and although my invention contemplates a primary purpose in providing a diathermic electrode for application in the treatment of senile hypertrophy of the prostate, nevertheless the features of my invention will be readily applicable to modified forms of instruments of great variety designed for a wide range of applicability.

My invention contemplates the application of an electrode to an internal or inaccessible organ by an insertion of the instrument through a body cavity; and more particularly, one embodiment of my invention contemplates the provision of an instrument which is designed and adapted to be applied per rectum to the prostate and the seminal vesicles.

An object of the invention is to provide an instrument which is constructed and arranged to permit adjustment thereof to facilitate insertion and removal with respect to a body cavity, and to render accidental displacement or removal, after a proper adjustment has been made, improbable and almost impossible.

A feature of my invention lies in providing an electrode surface or portion which is collapsible to facilitate insertion and removal, and which when uncollapsed presents a predetermined contact area of increased size and of a shape and disposition with respect to the rest of the instrument which prevents slipping or accidental expulsion from the cavity.

Another feature of the invention lies in providing means for controlling the adjustments of the electrode portion from an exposed and easily accessible portion of the instrument.

Another feature lies in constructing this control means in a manner which will indicate to the operator the relative adjustment of the contact portion which is disposed within the cavity.

In a preferred embodiment, the contact portion comprises a pair of members or sections which are relatively foldable like the covers of a book and which are constructed and arranged to present and provide a compact portion capable of easy insertion and withdrawal when folded, and which in unfolded or uncollapsed positions will present a contact portion having a predetermined configuration and disposition. In the embodiment herein described and illustrated, the contact members or sections are shaped to provide an uncollapsed electrode portion having a configuration which conforms substantially to the seminal vesicles when the instrument is applied through the anus into adjacent position with respect thereto.

A preferred embodiment contemplates the mounting of these members or sections upon the ends of closely positioned parallel spindles which extend outwardly through a body portion and are provided with manually controllable means at their free ends for causing rotation of the spindles and consequent adjustment of the contact members.

Another feature of the invention lies in designing and constructing the instrument with particular reference to the distribution and weight thereof so that the instrument will be self-supporting after it has been properly applied. More particularly, it is a feature of the invention to position the center of gravity toward the outer free end of the instrument, as by weighting the outer end of the body portion of the embodiment hereinbefore referred to. In this manner an instrument of the character herein described for application to the seminal vesicles may be rendered self-supporting when the patient is in the dorsal position, as will appear more fully hereinafter.

It is a further feature of the invention to provide electrical connecting means in an easily accessible manner, whereby one terminal of a proper electric circuit may be associated with the contact portion. And another feature lies in providing means for preventing short-circuiting of the instrument if the operation is performed upon a metal table.

For the attainment of the foregoing objects and such other objects as may herein-after appear or be pointed out, I have illustrated one form of my invention, viz., one embodiment of a prostatic electrode, in the accompanying drawings, in which—

Fig. 1 is a side elevational view of the instrument, with the contact portion in collapsed position;

Fig. 2 is an end elevational view taken from the forward portion of the instrument, and showing in dotted lines the positions assumed by the contact members after a certain adjustment has been made;

Fig. 3 is an end elevational view looking forwardly of the instrument from the rear or control end;

Fig. 4 is a plan view, shown partly in section, taken substantially along the line 4—4 of Fig. 1 and showing the contact portion in uncollapsed position; and

Fig. 5 is a cross-sectional view taken along the line 5—5 of Fig. 4, showing a detail of construction.

Referring to the drawings, and particularly to Fig. 1, it will be observed that I have shown an elongated, preferably cylindrical body portion 10 within which a contact portion 11 is mounted to project or extend forwardly of the body portion 10. The contact portion 11 may comprise a pair of contact members or sections 12 and 13 (Figs. 2 and 4), each of which comprises a substantially straight rear edge 14, an outwardly curved semi-circular end portion 15, an outer edge 16 substantially parallel to the edge 14, and a rear inwardly curved outer edge portion 17. The members 12 and 13 are arranged to be relatively adjustable, in a manner whereby the members 12 and 13 may be brought into superposition (Figs. 1 and 2), or into uncollapsed positions within a single plane (Fig. 4), the adjustability being preferably accomplished by making the members foldable and collapsible like the covers of a book about a hinge axis conforming substantially to the abutting inner edges 14.

For the purpose of controlling this relative adjustment of the contact members, I prefer to mount them upon rearwardly extending spindles 18 or 19 respectively, the spindles being mounted in closely parallel positions, extending longitudinally through the body portions 10, and mounted therein for rotation of each thereof about its axis. The spindles 18 and 19 are preferably of a width no greater than the width of the members 12 or 13, and are associated with the latter in a manner whereby the edges 14 will form a substantially straight continuation thereof.

For the purpose of preventing the spindles 18 and 19 from "riding" upon each other, I prefer to mount them within a sleeve

casing or bearing 20 carried by the body portion 10. Adjacent their rear or free ends, the spindles carry spur gears 21 or 22 respectively, these gears being of a size to permit them to mesh whereby rotation of one shaft will cause simultaneous rotation of the other. At their extreme ends, I prefer to provide the spindles with manually controllable means such as the grips 23 and 24 respectively, the latter comprising transverse pins threaded into or otherwise suitably associated with the spindles.

Preferably, the gears 21 and 22 are enclosed, and for this purpose, and the additional purpose of properly positioning the center of gravity of the device, I provide a conical end portion 25 for the body portion 10, the portion 25 having an end 26 of slightly reduced diameter with which a cap 27 may engage. The end 26 is of a longitudinal length much smaller than the length of the cap 27, so that a chamber is produced underneath the cap and outside of the portion 26 within which the gears 21 and 22 are accommodated.

Although details of construction are optional, I prefer to construct the body portion 10 of a cylindrical piece of insulating material molded about the sleeve bearing 20; and I prefer to extend the sleeve bearing 20 through the conical end 25 so that the latter will be held in abutment with the body portion 10 by the inside faces of the gears 21 and 22. The portion 25 is preferably made to diverge outwardly toward the free end of the instrument, and is advantageously made of metal whereby the proper weight is imparted to that end of the instrument. The outer periphery of the cover 27 is preferably made to constitute a continuation of the conical surface of the portion 25 so that the appearance of the device is not marred but presents a rather pleasing contour as clearly shown in Fig. 1. It will be understood that the end of the cap 27 is provided with parallel bores properly spaced to permit the spindles 18 and 19 to pass therethrough. I also prefer to provide the grips 23 and 24 with end portions which are bent outwardly, that is, away from each other, as clearly shown in Figs. 2 and 3, so that manipulation thereof will be facilitated. Preferably the grip members 23 and 24 have their inner ends extending outwardly from the spindles 18 and 19 in the same directions as the contact members 12 and 13, whereby the positions of the latter will be evident to the operator by the positions of the grip members 23 and 24.

The metallic end portion 25 is provided with an electric terminal 28 of any suitable construction or type whereby electrical connection may be established with the end portion 25 from an outside source. For the purpose of transmitting this electrical connection

tion to the contact portion at the forward end of the device, the sleeve bearing 20 may be made of metal.

The edges of the contact members 12 and 13 are suitably rounded off, and it will be observed upon viewing Fig. 1 that when the members are in superposed or collapsed positions, they provide and present a compact unit which is easily inserted into a constricted body cavity. In this connection, it will be noted that the semi-circular end portions 15 are particularly suitable for easy insertion thereof. It is also to be noted that the curved edge portions 17 constitute abutments after the contact portion has been unc�헤aked or unfolded which will prevent and render difficult undesired accidental withdrawal of the instrument.

In a preferred method of utilizing the instrument, the patient is caused to assume the dorsal position, the contact portion is inserted with the instrument in a substantially horizontal position, and thereupon the grips 23 and 24 are manipulated to unfold and uncollapse the contact portion so as to present a contact area of increased size and conforming substantially to the seminal vesicles. It will be understood that the instrument is inserted no further than to a degree at which the electrodes are totally within the cavity, although the amount of insertion will depend upon circumstances and requirements. By then releasing the instrument, the outer end thereof will tend to fall because of its weight, and in doing so the forward end, that is, the electrode surface, will be held firmly against the upper wall of the cavity and against the organs which are being treated. This depression of the outer end, and the formation of an abutment by the edge portions 17 tend to make the instrument entirely self-supporting, in addition to insuring firm and continued contact of the electrodes with the desired organs.

It will be understood that the indifferent electrode is applied to the patient's body at any other suitable portion thereof. For the purpose of preventing a short circuit of the electric current in case the operation is being performed upon a metal table, I provide legs 29 carried by the under portion of the conical end 25 and constructed of insulating material. If the outer end of the instrument should assume a depressed position which causes contact thereof with the table, the legs 29 will be the portions of the instrument which will so contact, and hence no short circuiting will occur.

It will be obvious that my invention may be applied to modified forms of instruments which may be designed for similar functions, and I do not mean to limit myself hereby to an electrode for the particular purposes herein described. It will also be obvious that the contact portion may be

rendered collapsible in a variety of ways, and the shape of the electrode sections may be varied to suit requirements. Other changes and alterations in the details herein described and illustrated for the purpose of explaining the nature of my invention may be made by those skilled in the art without departing from the spirit and scope of the invention as expressed in the appended claims; it is therefore intended that these details be interpreted as illustrative and not in a limiting sense.

What I claim is:

1. In an electrode of the character described, a pair of contact members which are relatively foldable like the covers of a book to permit easy insertion thereof into a body cavity when they are folded.

2. In an electrode of the character described, an elongated body portion, a pair of contact members carried at one end thereof and relatively foldable like the covers of a book along an axial line, said members having a configuration to provide a relatively compact mass when folded and to provide an increased contacting surface when unfolded.

3. In an electrode of the character described, an elongated body portion, a pair of contact members carried at one end thereof and relatively foldable like the covers of a book along an axial line, said members having a configuration to provide a relatively compact mass when folded and to provide an increased contacting surface when unfolded, and means associated with the other end of the body portion and operatively connected with the contact members for controlling the folding and unfolding thereof.

4. In an electrode of the character described, a substantially flat contact portion having a substantially U-shaped periphery and comprising relatively adjustable longitudinally symmetrical sections, said sections lying adjacent to each other on either side of the axis of symmetry, and means for adjusting said sections about said axis to bring them into super-position whereby insertion and removal of the contact portion with respect to a body cavity will be facilitated.

5. An electrode for application to the seminal vesicles, comprising a contact portion which is collapsible to facilitate insertion thereof into the anus and having an uncollapsed configuration conforming substantially to the area presented thereto by the seminal vesicles.

6. In an electrode of the character described, a contact portion comprising a pair of sections arranged and constructed to be collapsible into compact relation with respect to each other, said sections having rounded forward and rearward edges which facilitate insertion and removal of the col-

lapsed contact portion with respect to a body cavity, and said sections having configurations which complement each other to present a continuous electrode surface having a U-shaped periphery when the sections are uncollapsed after the insertion has been accomplished.

7. In an electrode of the character described, collapsible contact members adapted to be inserted into a body cavity when collapsed, and means for uncollapsing said members after insertion thereof to present an increased contacting surface within the cavity, said means comprising cooperating spindles carried thereby, and manually operable means associated therewith for controlling the cooperation thereof.

8. In an electrode of the character described, collapsible contact members adapted to be inserted into a body cavity when collapsed, and means for uncollapsing said members after insertion thereof to present an increased contacting surface within the cavity, said means comprising spindles carried by the members, and manually operable means carried thereby for causing rotation thereof.

9. In an electrode of the character described, an elongated body portion, relatively adjustable contact members extending from one end thereof, and means for controlling the adjustment from the other end thereof, said means comprising spindles associated with the members and extending through and rotatably mounted within the body portion, and means for rotating said spindles.

10. In an electrode of the character described, an elongated body portion, relatively adjustable contact members extending from one end thereof, and means for controlling the adjustment from the other end thereof, said means comprising spindles associated with the members and extending through and rotatably mounted within the body portion, and means for rotating said spindles, said last named means including meshing gears carried by the spindles whereby rotation of one spindle will cause rotation of the other.

11. In an electrode of the character described, an elongated body portion, a collapsible contact portion carried at one end thereof, and means for accomplishing the collapsing and uncollapsing of the latter, said means comprising a double barreled sleeve bearing extending through the body portion, a pair of spindles associated with the contact portion and mounted for rotation

within said bearing, and manual grips carried by the free ends of said spindles.

12. In an electrode of the character described, an elongated body portion; a collapsible contact portion carried at one end thereof; means for accomplishing the collapsing and uncollapsing, said means comprising a double barreled metallic sleeve bearing extending through the body portion, and a pair of spindles associated with the contact portion and mounted for rotation within said bearing; and means for establishing electrical connection between the free end of the body portion and the contact portion, said last named means comprising a metallic end portion mounted upon said bearing, and an electric terminal associated therewith.

13. In an electrode of the character described, an elongated body portion, and a collapsible contact portion at one end thereof adapted to be inserted into a body cavity when collapsed, the assembled electrode being so designed with respect to weight distribution as to position the center of gravity thereof adjacent to one end thereof.

14. In an electrode of the character described, an elongated body portion, and a collapsible contact portion carried at one end thereof and adapted to be inserted into a body cavity when collapsed, the other end of the body portion being weighted to hold the contact portion against the upper wall of the cavity.

15. In an electrode of the character described, an elongated body portion, a collapsible contact portion carried at one end thereof and adapted to be inserted into a body cavity when collapsed, means for uncollapsing the contact portion after the insertion thereof, and the free end of the body portion being weighted so as to hold the uncollapsed contact portion against the upper wall of the cavity.

16. In an instrument of the character described, an elongated body portion, an electrode portion at one end thereof for insertion into a body cavity, electrical connection means at the other end thereof, said means and electrode portion being in electrical communication, and insulating legs carried by the end of the instrument opposite the electrode portion, whereby contact between the exposed portion of the instrument and a support will take place, if at all, through said insulating legs.

In witness whereof, I have signed this specification this 5th day of January, 1926.

MAXIMILIAN STERN.
